ABSTRACT

A bulk lot of silicone fluid, precharged with Freon or Genetron 11, contained in a storage drum. At the site of use a nitrogen tank and a spray nozzle are connected to fittings through the drum head.

INVENTOR:
CARL H. CAMPBELL
BY ATTORNEY,

**METHOD OF DISPENSING AN INDUSTRIAL SPRAY
USING BOTH A PROPELLANT-DISPERSANT AND GAS
PRESSURE**

BACKGROUND OF THE INVENTION

This invention relates to compositions and methods for spraying a liquid vehicle onto a surface, and in particular to industrial sprays. It has particular application to applying liquid silicone coatings to surfaces industrially, but its usefulness is not limited thereto.

Numerous liquids are now packaged in small aerosol containers which hold a mixture of the liquid vehicle and a relatively low-pressure propellant. The propellant both expels the liquid vehicle from the container and atomizes the liquid vehicle in a fine spray pattern. The use of such a container for large amounts of liquid, such as are used in industrial applications, has proven impractical.

One of the objects of this invention is to provide an industrial spray composition and a method of applying it which will approximate the finely atomized spray pattern obtained with aerosol containers.

Another object of this invention is to provide such a method in which the liquid being sprayed can easily be maintained in a sanitary condition.

Other objects will become apparent to those skilled in the art in the light of the following description and accompanying drawing.

SUMMARY OF THE INVENTION

In accordance with this invention, generally stated, an industrial spray composition is provided in which a liquid vehicle is precharged with low-pressure propellant which serves as a dispersant. Under the prescribed conditions of use of the spray, the pressure generated by this low-pressure propellant-dispersant is insufficient to move the spray composition effectively through a spray nozzle, but the propellant-dispersant does aid in atomizing the liquid vehicle when another propellant is introduced which provides the desired transporting pressure. The liquid vehicle and low-pressure propellant-dispersant are packed in a bulk container, the container is transferred to the place at which the spray is to be applied, and a source of pressurized gas is connected to the container through a coupling on a tube extending through the head of the container. An outlet spray system, consisting in the preferred embodiment of the method of this invention of a flexible hose and a standard adjustable nozzle, is connected through a coupling on a dip tube extending through the head of the container nearly to the bottom of the container. In the preferred embodiment the liquid vehicle is silicone fluid, the low-pressure propellant-dispersant is trichlorofluoromethane, sold as Freon 11 or Genetron 11, the container is a standard heavy gauge 55-gallon storage drum, and the high-pressure gas is nitrogen delivered from a standard tank through a pressure control valve and gauge at a gauge pressure within the range of 15 to 40 p.s.i.

BRIEF DESCRIPTION OF THE DRAWING

In the drawing, FIG. 1 is a view in perspective of one illustrative embodiment of a spray apparatus for use with the industrial spray composition and method of this invention.

DESCRIPTION OF THE PREFERRED EMBODIMENT

Referring now to the drawing, reference numeral 1 indicates one illustrative embodiment of a spray apparatus for use with the industrial spray and method of this invention. The apparatus 1 includes a 55-gallon drum 2. Extending into the drum 2 through the head 3 of the drum 2 are a short inlet tube 4 mounted through a gastight cap 5 screwed onto a standard fitting 18 on the head 3 and a long outlet tube 6 mounted through a gastight cap 7 screwed onto a standard fitting 19 on the head 3. The low end of the outlet tube 6 extends to within

one-half inch of the bottom 8 of the drum 2. The upper end of the inlet tube 4 is connected by a coupling 9 to a hose 15, a pressure gauge 11, a hose 16, and to a pressure-regulating valve 12 on a tank 10 of pressurized nitrogen. The upper end 5 of the outlet tube 6 is connected by a coupling 12 to a flexible hose 13. On the free end of the hose 13 is mounted a spray nozzle 14, such as a Binks or DeVilbiss adjustable spray nozzle.

To assure a sanitary spray, the hoses 13, 15 and 16 are all 10 made of clear plastic, and sanitary fittings are used throughout.

The apparatus 1 is used as follows in carrying out the method of this invention in applying a liquid silicone coating to a surface. At a factory, a bulk quantity of silicone fluid is 15 charged with low-pressure propellant-dispersant. The silicone fluid may have a viscosity of 350 centistokes and the propellant-dispersant maybe trichlorofluoromethane sold as Freon 11 or Genetron 11 which will be referred to generally hereinafter as propellant 11. An illustrative satisfactory fill in 20 a 55-gallon drum is 24 pounds of silicone fluid, 276 pounds propellant 11, mixed at a temperature below 24° C. The drum 2 is filled with the cool mixture of silicone and incorporated propellant 11 and the couplings 9 and 12 or the fittings 18 and 19 as shipping conditions dictate, are capped.

25 The drum 2 is then transported to the place at which the silicone is to be sprayed on a surface. At this location, after it is ascertained that the temperature of the contents of the drum is less than 24° C., the rest of the spraying system is assembled by installing the tubes 4 and 6, if necessary, and attaching the 30 hoses 15 and 13 to the couplings 9 and 12. The pressure control valve is adjusted to give a desired pressure in the range between 15 and 40 p.s.i. The contents of the drum are preferably warmed to within the range of 24-35° C. The nozzle 14 is then adjusted to give the desired spray pattern, and 35 the surface to be coated is sprayed in a conventional manner. The temperature of the contents of the drum during the spray operation should be slightly above 24° C., but preferably not over 35° C.

The method of this invention produces a finely atomized 40 spray pattern, approximating that of an aerosol container, simply, economically, and with a minimum of danger.

Numerous variations in the method of this invention, within the scope of the appended claims, will become apparent to those skilled in the art in the light of the foregoing disclosure. 45 Merely by way of example, the viscosity of the silicone fluid can be varied, other coating materials can be employed, other low-pressure propellants can be used, although propellant 11 has almost ideal characteristics, the proportions of coating material and propellant-dispersant can be varied to accommodate different viscosities of coating material and types of coating and propellant-dispersants, and other inter high-pressure gases, including compressed air, may be used as the transporting propellant. These are merely illustrative.

Having thus described the invention what is claimed and 55 desired to be secured by Letters Patent is:

1. The method of using an industrial spray comprising connecting to a container, containing a liquid spray vehicle charged with several times its weight of low-pressure propellant-dispersant with a vapor pressure insufficient to generate 60 the desired transporting pressure under the expected conditions of use of said spray, a source of high pressure gas having a pressure substantially higher than the vapor pressure of said propellant-dispersant and thereby forcing said spray vehicle and propellant-dispersant through a spray nozzle.
2. The method of claim 1 wherein the liquid spray vehicle is 65 silicone fluid.
3. The method of claim 2 wherein the high-pressure gas is delivered into said container at a gauge pressure in the range of 15 to 40 p.s.i.
4. The method of claim 2 wherein the low-pressure propellant-dispersant is trichlorofluoromethane.
